UNITED STATES PATENT OFFICE.

RICHARD E. JONES, OF PEARL RIVER, NEW YORK, ASSIGNOR TO DEXTER FOLDER COMPANY, A CORPORATION OF NEW YORK.

PAPER-FEEDING MACHINE.

1,062,336.

Specification of Letters Patent. Patented May 20, 1913.

Application filed January 24, 1912. Serial No. 673,231.

To all whom it may concern:

Be it known that I, RICHARD E. JONES, a citizen of the United States, and a resident of Pearl River, in the county of Rockland 5 and State of New York, have invented certain new and useful Improvements in Paper-Feeding Machines, of which the following is a full and clear specification.

In the patent of Dexter *et al.*, No. 779,914, granted January 10th, 1905, is disclosed a sheet caliper device for paper feeding machines in which the operation of the feeding machine is thrown out by the attempted passage of an extra thickness of sheets from 10 the pile. In this patented mechanism a clutch operating rock shaft is controlled by a suitable cam and the sheet actuated caliper device so that in the normal operation of the machine in passing successive single 15 sheets, the clutch is retained in active position, but is in readiness to operate periodically in the event of the detection by the caliper device of an extra thickness of sheets. The mechanism of this patent has 20 gone largely into use and has given considerable satisfaction in accomplishing the results aimed at, but it has been found from practice that while the mechanism will arrest the operation of the machine under the 25 control of the caliper device, the momentum or racing of the machine at the time the clutch is thrown out, is frequently sufficient to carry forward the objectionable extra thickness of sheets onto the conveyer 30 before the machine is actually stopped, so as to require considerable time and trouble in removing the improperly fed sheets before the feeding operation can be resumed.

With this objection in view, the present 35 invention may be considered as an improvement upon the structure of the above named patent, and to this end the present invention consists of combining with a sheet caliper controlling device of the type referred 40 to, suitable means for automatically preventing the action of the drop roller sheet delivery mechanism when the machine is thrown out by the sheet caliper device.

In order that my invention may be fully 45 understood I will first describe the same with reference to the accompanying drawings and afterward point out the novelty more particularly in the annexed claims.

In said drawings Figure 1 is a vertical 50 longitudinal sectional elevation of part of

a paper feeding machine embodying the present invention and showing in full and dotted lines the change in positions of the parts during the normal operation of the machine. Fig. 2 is a similar view illustrating in full and dotted lines the change in position of the parts when the machine is thrown out by the automatic action of the present invention. Fig. 3 is a detail front elevation of the parts shown in Figs. 1 and 2. 60 65

I have shown in the drawings only enough of the well known automatic paper feeding machine to illustrate the action of the present invention.

1 represents part of the main frame of the 70 paper feeding machine, P, indicates a portion of the pile of sheets which are mounted upon the usual automatically elevated table or platform.

10 is the cam shaft or main operating 75 shaft from which all of the parts of the paper feeder are driven in this type of machine. This shaft 10 is equipped with a suitable controlling clutch (not shown), such for example as illustrated in the patent of 80 Dexter, No. 663,672 of December 11, 1900. Upon the shaft 10 is mounted a clutch controlling cam 15 upon the periphery of which operates an anti-friction roller 16 freely journaled in the end of a rock arm 17 85 keyed to a transverse rock shaft 18 freely journaled in the side frames of the machine. This rock shaft 18 is a clutch operating or controlling shaft by which the main clutch of the feeder is thrown into and out of operation. The controlling of the clutch in 90 this type of machines by the rocking movement of the shaft such as 18 is so well known in the art that the mechanism by which the clutch is controlled is not illustrated in the 95 accompanying drawings. The rock arm 17 is formed with a laterally projecting nose 20 which normally rests just above the upper end 53^a of a caliper operated lever presently 100 to be explained.

30 is the lower rotary member of the sheet caliper device mounted upon a transverse shaft 31 at the delivery end of the feeding machine beneath the plane of feed of the sheets. This shaft 31 is the lower 105 feed shaft which carries a plurality of lower feed rollers such as at 32 with which cooperate the drop rollers indicated at 33, freely journaled upon the forward ends of rock arms 34 projecting from a rock shaft 110

35 journaled in the side frames of the machine and operated by the usual controlling cam mechanism which is not shown.

40 is the upper normally stationary rotatable caliper member shown in the form of a segment journaled at 41 upon a laterally projecting bearing member 42 of an angular bracket 43 which is pivotally mounted at 44 forwardly of the journal 41 referred to. The bracket 43 is pivoted upon a rigid bracket arm 45 projecting inwardly from the side frame of the machine. The upper end of the bracket 43 is connected by a spring 46 with the bracket 45 and is adjusted upon its pivot 44 by means of an adjusting screw 47 threaded through the bracket 43 engaging a lug 48 projecting laterally from bracket 45.

The rotary caliper segment or member 40 carries above its journal 41 a laterally projecting pin 50 which rests beneath the lower arm 51 of a lateral extension 52 of lever 53 which is pivotally mounted at 54 upon an upper extension 45^a of bracket 45. This lever 53 has its upper end 53^a resting beneath the nose 20 as above referred to.

The mechanism so far as specifically described is essentially the same as illustrated in the above named Patent No. 779,914 and it will be understood by referring to said patent that the passage of an abnormal thickness of sheets between the caliper members 30 and 40 will rock the lever 53 either by the rotation of caliper member 40 or by the vertical yielding of bracket member 43 upon its pivot 44, thereby moving the end 53^a from beneath the nose 20 to permit the rock arm 17 to fall when the anti-friction roller 16 reaches the low part of the controlling cam 15. In addition to this result, my present invention includes means for preventing the continued operation of the drop roller delivery mechanism by the racing or momentum of the machine. To accomplish this I mount upon the clutch operating rock shaft 18 an inwardly presented rock arm 60 and I mount upon the drop roller rock shaft 35 a long upwardly presented rock arm 65 whose upper end normally rests a little in front of and just beneath the forward end of said rock arm 60 as shown in full lines in Figs. 1 and 2. From this it will be observed that in the normal operation of the machine with the clutch operating rock shaft 18 held against motion by the controlling cam 15 and caliper operated lever 53 that the rock arm 65 upon rock shaft 35 will rock rearwardly beneath the rock arm 60 every time the drop rollers 33 move into engagement with the sheet above the lower feed rollers 32. When, however, the caliper mechanism is actuated by an extra thickness of sheets so that the rock arm 17 is released and the rock shaft 18 is rocked, the arm 60 will fall

sufficiently to engage behind the upper end of rock arm 65 and thereby prevent the lowering of the drop rollers 33 into operative position. The normal working of the drop roller mechanism is illustrated in Fig. 1 and the arrested position of this mechanism is shown in dotted lines in Fig. 2.

With this improved mechanism it will be understood that the improper thickness of sheets cannot be carried past the delivery mechanism of the feeding machine so that it is a much simpler and quicker operation to replace the improper sheets and resume the normal operation of the feeding machine.

What I claim is:

1. The combination with a machine through which sheets of paper are passed, of sheet delivery mechanism adapted to be intermittently operated, means movable into and out of position to hold said mechanism inoperative, other means for holding the first said means inoperative, and sheet caliper means movable into operative engagement with said other means.

2. The combination with a machine through which sheets of paper are passed, of sheet delivery mechanism adapted to be intermittently operated, a rock arm adapted to move into a position in which it holds said delivery mechanism inoperative, means normally retaining said rock arm inoperative, and sheet caliper means adapted to be moved into positive operating engagement with said rock arm retaining means by an abnormal thickness of sheets to release said rock arm.

3. The combination with a machine through which sheets of paper are passed, and a drop roller rock shaft provided with an arm projecting therefrom, a controlling rock shaft also provided with an arm projecting therefrom, a lever normally holding said controlling rock shaft inoperative with its projecting arm normally out of the path of the arm projecting from the drop roller rock shaft and a caliper device adapted to be moved into displacing engagement with said holding lever, by an abnormal thickness of sheets.

4. The combination with a machine through which sheets of paper are passed, drop roller delivery mechanism for said machine, and suitable throw out mechanism adapted to arrest the operation of said machine, of a sheet caliper device adapted to be operated by an abnormal thickness of sheets, a lever controlling said throw out mechanism and adapted to be positively engaged by said caliper device, and means actuated by said throw out mechanism adapted to independently arrest the operation of said drop roller mechanism.

5. The combination with a machine through which sheets of paper are passed,

drop roller delivery mechanism for said machine, suitable throw out mechanism adapted to arrest the operation of said machine and operating means for said throw out mechanism, of a sheet caliper device adapted to be operated by an abnormal thickness of sheets, a lever controlling said throw out operating means adapted to be displaced by positive engagement with said caliper device, and means actuated by said throw out operating means adapted to independently engage and arrest the operation of said drop roller mechanism.

6. The combination with a machine 15 through which sheets of paper are passed, of suitable throw out mechanism including a rock shaft adapted to arrest the operation of said machine, drop roller delivery mechanism including a rock shaft supporting the drop rollers, coöperating arms projecting from the throw out operating rock shaft and said drop roller rock shaft, a lever adapted to hold the throw-out rock shaft inoperative, and a sheet caliper device 20 controlling the action of said lever for holding the throw out operating rock shaft.

7. The combination with a machine through which sheets of paper are passed and suitable and throw out mechanism for

said machine including a controlling rock 30 shaft, of a rock arm projecting from said controlling rock shaft, a lever resting normally in the path of said rock arm to prevent the operation of said rock shaft, a sheet caliper device controlling said lever, a 35 drop roller delivery mechanism including a rock shaft supporting the drop rollers, a controlling arm extending from said drop roller rock shaft, and an arm projecting from said throw out controlling rock shaft 40 supported normally out of engagement with said drop roller arm and adapted to engage therewith when the throw out rock shaft is operated.

8. The combination with a machine 45 through which sheets of paper may be passed, of drop roller delivery mechanism, means adapted to block the movement of said delivery mechanism, a lever normally holding said blocking means inoperative, 50 and a sheet caliper wheel provided with a projection adapted to displace said lever to permit said blocking means to become operative.
